UNITED STATES PATENT OFFICE.

ABRAHAM ELKINS, OF BROOKLYN, NEW YORK.

ASH-RECEPTACLE.

1,321,725.

Specification of Letters Patent. Patented Nov. 11, 1919.

Application filed February 15, 1919. Serial No. 277,223.

To all whom it may concern:

Be it known that I, ABRAHAM ELKINS, a citizen of the United States, residing at Brooklyn, in the county of Kings and State 5 of New York, have invented new and useful Improvements in Ash-Receptacles, of which the following is a specification.

This invention relates to ash sifters and has for its primary object the provision of 10 a receptacle having a dust collecting section and movable reticulated means overlying said section and adapted to support an ash tray or container in sifting position with respect thereto so that when said means is 15 actuated, the ashes contained in said tray or container will be agitated and the dust discharged to the collecting section of the structure during the sifting operation.

A still further object of the invention is 20 to provide an ash sifter in which that type of tray or pan customarily used in the ash pit of a stove may be readily associated with the movable agitating means of the device.

Another object of the invention resides in 25 the general construction of a sifter in which the sifting operation may be carried on without undue labor on part of the operator and without the scattering or distribution of dust on the outside of the sifter during 30 the sifting operation.

Referring to the drawings:-

Figure 1 is a front view of the sifter showing the swinging closure adjusted to an opened position.

Fig. 2 is a vertical section therethrough taken on the line 2-2 of Fig. 1.

Fig. 3 is a horizontal section taken on the line 3-3 of Fig. 1.

Fig. 4 is a perspective view of the agitating frame or member.

Fig. 5 is a perspective view of the ash tray.

The invention comprises a suitable receptacle 10 which in the present instance, is 45 of rectangular form and constructed of metal. However, in this respect, I do not wish to be limited as there may be many obvious shapes that would be just as beneficial, likewise, I do not wish to confine myself to the use of metal but find same highly preferable in view of its being highly durable and fire proof.

The receptacle is provided at one side near its top with an opening 11 adapted to 55 be sealed during the sifting operation by a swinging closure 12, the latter having a pro-

jection portion 13 conforming with the shape of the opening 11 and adapted to snugly fit therein whereby to seal the joint perfectly between the opening and the 60 closure and prevent the escape of dust to the outside during the sifting operation. The swinging closure may be held operatively extended over the opening by means of suitable keepers 14 mounted upon the 65 front wall of the receptacle above the opening 11.

At one end, the receptacle is provided with an opening 15, to accommodate a removable 70 slidably mounted dust collecting drawer 16, the same being arranged to freely rest upon the bottom wall of the receptacle as shown in Fig. 2. The opening 15 is normally sealed by a sliding cover plate 17 having side flanges 18 operatively associated with 75 continuous vertical flanges 19 of the receptacle whereby the closure plate may be moved in a vertical direction. The flanges 19 exceed the length of the closure plate so that when the latter is adjusted to permit 80 of insertion of the drawer in the receptacle or removal of the same therefrom, the closure plate will be maintained in a relatively fixed adjusted position through frictional contact of the flanges 18 with said 85 flanges 19.

At a point above the drawer 16 and disposed in horizontal alignment with the opening 11 is a movable member or agitator frame 20 which includes end sections 21 90 having bars 22-22 suitably secured to the longitudinal bars 23-23 of a rectangular section 24. The vertical bars 25 of said end sections 21 and the vertical bars 26 of said section 24 are connected together by braces 95 27 and as illustrated said braces are provided with trunnions 28 and 29 respectively which find bearings in the end walls of the receptacle 10, the bearing 29 having a manipulating handle 30 which is normally engaged 100 with a stop 31 on the adjacent end wall of the receptacle 10. From the construction of the agitator member or frame as above described, it will be seen that it is substantially open at all sides whereby to permit 105 of its accommodating an ash tray or receiver of the type shown at 32. This tray is open at one side as at 33. It is of a design which will permit of its being normally arranged in the ash pit of a stove so that when sufficient ashes have been collected, the tray 110 may be placed in the agitator frame ready

for the sifting operation. One side of the agitator frame is closed by a reticulated wall 34 which extends over the open side 33 of the tray 32 when the latter is correctly positioned in the agitator for the sifting operation. The open side 35 of the agitator frame may be held in fixed alinement with the opening 11 in the receptacle 10 by engagement of the handle 30 with the mentioned stop 31. This facilitates the application of the tray to the agitator frame or removal of the same therefrom.

The braces 27—27 are respectively provided with extensions 36 and 37, the former having an opening 38 therein and the latter, a recess 39. After the tray has been inserted in the agitator frame for the sifting operation, a securing or locking bar 40 is applied across the open side 35 of said agitator frame and against one side of the tray 32 and as shown in Figs. 1 and 2, one end of said bar is freely receivable in the opening 38 and the other end likewise receivable in the recess 39. The recess 39 has an offset 41 in one of its vertical edges whereby the bar 40 may be sprung to engage in said offset. The springing of the bar is effected by providing the bar with a circular enlargement 42 adapted to engage with one side of tray 32 as clearly shown in Figs. 1 and 2.

After the tray 32 has been securely adjusted to the agitator frame, the closure 12 is adjusted over the opening 11 and by moving the handle 30 back and forth, the agitator frame and the tray 32 will be revolved or oscillated about its axis and the contents of the tray thoroughly agitated, the dust falling through the meshes of the bottom 34 and the cinders or unburnt particles of coal remaining in the tray 32. The cover plate 17 is provided with a suitable manipulating extension 43.

What is claimed as new is:—

An ash sifter comprising supporting means, a frame capable of movement about its axis in the supporting means, said frame being of rectangular form in cross-section and open at one side to receive an ash-tray and having a forward rectangular section, and end sections connected at their ends to and extending rearwardly from said forward section and also having end braces equipped with trunnions and forming stops at the back of the frame, and a foraminous wall at right angles to said open side and stops; and means for fastening a tray in said frame.

In testimony whereof I have affixed my signature.

ABRAHAM ELKINS.
